UNITED STATES PATENT OFFICE.

WILLIAM DUBILIER, OF NEW ROCHELLE, NEW YORK.

TELEPHONE RECEIVER.

Application filed May 29, 1922, Serial No. 564,539. Renewed June 3, 1926.

This invention has for one of its purposes to provide an improved type of telephone receiver such as is used for telegraph and telephone purposes with a flexible vibrating diaphragm.

Another object is the provision of telephone receiver in which separate paths are provided for the lines of force of the electro-magnet and of the permanent magnet.

10 Still another object is the provision in a telephone receiver of a by-pass for the electro-magnetic lines of force.

Still another object is the provision of a telephone receiver in which the core of the 15 electro-magnet is composed of a plurality of insulated elements.

These objects are attained by the novel construction, combination and arrangement of parts hereinafter described and shown in 20 the accompanying drawings, forming an essential part of this disclosure and in which;

Figure 1 is a diagrammatic side elevational view showing a conventional type of permanent magnet having an adaption of 25 the invention incorporated therein and illustrating its application with reference to a diaphragm.

Figure 2 is a plan view of a receiver showing cover removed to disclose the interior.

Figure 3 is a transverse sectional view taken on line 3—3— of Figure 2, with the cover applied.

The numeral 10 is used in Figure 1 to 35 designate the looped portion of common type of permanent magnet, from the ends of which extend the pole pieces 11 and 11'.

Held between these pole pieces are the 40 arms 12 and 12' of a U shaped core 13 made of soft iron and interjacent the arms and poles are strips of non-magnetic material 14 and 14', the base of the core element 13 acting as a by-pass for the electro-magnetic lines of force.

45 A coil 15 of wire encircles the pole piece 11 and arm 12 continuing as at 16 and to coil 15' and encircling the opposite pole 11' and arm 12', this wire being in electrical engagement with the source of electrical 50 energy.

A diaphragm 17, held at its peripheral edges by clamp supports 18, will obviously be attracted and repelled by forces flowing from the combined ends of the magnets as 55 the coils are energized.

When used as a telephone receiver a weak

alternating current passes through the electro-magnet, setting up an alternating electro-magnetic field. In the common type of telephone receiver used at present, the alternating magnetic lines must travel through the permanent magnet which offers a tremendous resistance, or through the air which also has a very great reluctance thus offering a great resistance to the alternating 60 electro-magnetic lines of force.

I have found that by dividing the core of the electro-magnet into two parts as described above, a path of the least possible resistance is offered for the electro-magnetic 70 lines of force, but without destroying the effect of the permanent magnet, with the result that we obtain much more efficient operation.

The U shaped core element 13 is made 75 preferably of laminated sheets of soft iron or steel and the pole piece 11 and 11' of the permanent magnet 10 are also preferably made of soft iron or steel as is well known in the construction of cores for electro-magnets.

Due to the shape of the soft iron core element 13, a path of the least resistance is provided for the electro-magnetic lines of force, the gap between the poles being essentially bridged, and the energy directed to the diaphragm 17 in a manner which will be readily understood.

In Figures 2 and 3 of drawing I have shown an embodiment of my invention in 80 what is commonly known as a watch-case type receiver.

The inner ends of the strips 27 and 27' are turned vertically upward at a right angle, forming poles 29 and 29', and between 95 them are supplementary pole arms 31 and 31' formed with a connecting base 32 substantially as before described as a U shaped core element, the adjacent pole arms being insulated one from the other by non-magnetic material 33 and 33'.

100 Each magnet core so formed has wound upon it, coils 34 and 34', connected at 35 and having their opposite ends in circuit with a source of electric energy.

105 Thus it will be seen that the core of each magnet is comprised of two distinct core elements and that these elements are integral with each other, making a shorter path for electro-magnetic lines of force than exists between the ends of the combined poles and arms and the diaphragm 23, rendering its 110

response more sensitive and prompt in its vibration fluctuations.

Both of the embodiments illustrated are substantially alike and present means for increasing efficiency of operation by the use of a closed electro-magnetic field, and an air gap only between the pole pieces and the diaphragm.

However, as changes of construction could be made within the scope of the invention, it is intended that all matter contained in the foregoing description, or shown in the accompanying drawings, shall be interpreted as being illustrative and not in a limiting sense.

Having thus described my invention what I claim as new and desire to secure by Letters Patent, is:—

1. A telephone receiver comprising a diaphragm, a magnet having a pole piece presented to the diaphragm, a second magnet including arms having their extremities in proximity to the diaphragm to act thereon, and a coil encircling said magnets, the second magnet providing a path of relatively low reluctance.

2. A telephone receiver comprising a diaphragm, a magnet having a pole piece presented to the diaphragm, a second magnet including arms having their extremities in proximity to the diaphragm to act thereon, and a coil encircling said magnets, the second magnet providing a path of relatively low reluctance, said second magnet being out of magnetic contact with the first magnet.

3. A telephone receiver comprising a diaphragm, a magnet having a pole piece presented to the diaphragm, a second magnet including arms having their extremities in proximity to the diaphragm to act thereon,

and a coil encircling the pole piece and an arm of the second magnet, the second magnet providing a path of relatively low reluctance.

4. A telephone receiver including a diaphragm, a magnet having a pole piece presented to the diaphragm, a second magnet including arms having their extremities in proximity to the diaphragm to act thereon, and a coil encircling the pole piece and an arm of the second magnet, the second magnet providing a path of relatively low reluctance, the second magnet being out of magnetic contact with the first magnet.

5. A telephone receiver comprising a diaphragm, a magnet having pole pieces presented to the diaphragm, a second magnet including a pair of connected arms between said pole pieces, the extremities of said arms being in proximity to the diaphragm to act thereon, and windings encircling each pole piece and the arm adjacent thereto, the second magnet providing a path of relatively low reluctance between said pole pieces.

6. A telephone receiver comprising a diaphragm, a magnet having pole pieces presented to the diaphragm, a second magnet including a pair of connected arms between said pole pieces, the extremities of said arms being in proximity to the diaphragm to act thereon, and windings encircling each pole piece and the arm adjacent thereto, the second magnet providing a path of relatively low reluctance between said pole pieces, the arms of the second magnet being out of magnetic contact with said pole pieces.

Signed at New York in the county of New York and State of New York this 19th day of May A. D. 1922.

WILLIAM DUBILIER.
